UNITED STATES PATENT OFFICE.

GEORGE B. PICKOP AND WILBUR R. CORBIN, OF NEW BRITAIN, CONNECTICUT, ASSIGNORS TO P. & F. CORBIN, OF NEW BRITAIN, CONNECTICUT, A CORPORATION OF CONNECTICUT.

SASH-BALANCE.

SPECIFICATION forming part of Letters Patent No. 700,814, dated May 27, 1902.

Application filed February 27, 1902. Serial No. 96,002. (No model.)

To all whom it may concern:

Be it known that we, GEORGE B. PICKOP and WILBUR R. CORBIN, citizens of the United States, residing at New Britain, county of 5 Hartford, State of Connecticut, have invented certain new and useful Improvements in Sash-Balances, of which the following is a full, clear, and exact description.

Our invention relates to what we may term 10 a "sash - balance - operating" mechanism which may be employed in connection with double sliding window-sash.

The object of the invention is to provide 15 simple and effective means whereby the raising of one window will lower the other, or, vice versa, whereby either of the windows may be moved up or down at will, and whereby the windows, or either of them, may be set at any desired position, open or closed, and there 20 locked.

The invention does away with the use of 25 sash cords and weights such as are commonly employed and in other ways embodies advantages obvious to one skilled in the art and as will be understood from a reading of the following specification and an examination of the drawings.

In the drawings, Figure 1 is a conventional 30 view, in front elevation, of a window-sash fitted with our improved operating mechanism. Fig. 2 is a fragmentary view, relatively enlarged, of certain parts of our invention. Fig. 3 is a similar view to Fig. 2, parts being shown in a different position. Fig. 4 is a horizontal section on the line 4-4 of the apparatus 35 as it appears in Fig. 1, the parts being relatively enlarged. Fig. 5 is an elevation of the inner end of the improved mechanism drawn to a scale similar to Fig. 4.

40 A B are windows movable in suitable guide-ways in the window-casing.

A' B' are toothed racks carried by the windows A B, respectively, at or near the side thereof. These racks are preferably formed 45 of sheet metal.

C D are gear-wheels in mesh with the racks B' A', respectively. The gear-wheel C is carried by a shaft or spindle E. The gear-wheel D is carried by a sleeve or hub F, which has 50 a rotative bearing upon the spindle E. G is

another sleeve in line with the sleeve F and also having a bearing upon the spindle E. The sleeve F may rotate upon the spindle E; but the sleeve G is prevented from rotating thereon by means of a bearing at the outer end 55 of said sleeve G upon the square end E' of said spindle. Consequently while the sleeve G may revolve with the spindle E it may be moved longitudinally thereon, the length of the square bearing E' being sufficient to give 60 the desired freedom of longitudinal movement. The adjacent ends of the sleeves F and G are provided with deep teeth F' G', which may mesh with each other or be freed from each other at the will of the operator and 65 for the purpose hereinafter described.

Upon the outer end of the sleeve G is a circular rack G², formed by annular ridges, and H is a member rotatably mounted in the lug extensions I I upon the case or housing J. 70 The member H performs the function of a pinion, in that it is preferably toothed to engage with the circular rack G², so that the said member H may be constantly in mesh with said rack G². Manifestly the rotation of the 75 member H will move the sleeve G longitudinally upon the spindle E, and by this means the teeth G' may be partially or entirely freed from engagement with the teeth F' upon sleeve F.

K is a spring secured at one end to the case J and at the other end to the sleeve F.

L is a spring which may be secured at one end to the case J and at the other end to the 85 sleeve G.

The function of the springs K and L is as follows: Assuming the sash A to be the lower sash, it will be seen that the rack A' engages with the geared wheel D. Consequently when the window is raised the sleeve F will be rotated. In order to permit the user to easily raise the window A, the said spring K is under its highest tension when the window A is in its lowermost position. Consequently the tendency of the spring K will be to lift the 90 window. By properly adjusting the tension it may be such that it will require but little force upon the operator's part to lift said window A, the tension of the spring supplying the balance of the needed power. When the 95 window A is raised the sleeve F will be rotated in the opposite direction, so that the tension of the spring K will be relieved. Consequently the 100 tendency of the spring L will be to lift the window A.

window B, which may be assumed to be the uppermost window, is raised to its highest position, the spring L is under its lowest tension. As the window B is lowered the gear C is rotated and the spindle E will rotate the sleeve G through the square bearing E'. This rotation of the sleeve G winds up the spring L, and therefore increases the tension therein. Consequently when the operator desires to raise the upper window B but little force is needed, the balance of the power being supplied by the spring L. Upon that portion of the sleeve G outside of the case J are formed teeth G³, and upon the adjacent portion of the case J are formed corresponding teeth J'. This is best seen in Figs. 2 and 3. These teeth J' and G³ are shorter than the teeth F' and G'. In practice it is our custom to make the former about half the length of the latter. The reason for this will be understood from the description of the operation of the device.

M is an operating-handle, which may be in the form of a crank-arm extending from the member H, which we shall term herein as the "controlling" member. The lever M we shall refer to herein as the "controlling-handle."

N is a rack which is by preference provided with notches—say three in number, as shown in Figs. 2 and 3. The operating-handle M yieldingly bears in any one of the notches in said rack N and is frictionally retained in any one of the three positions. We have designated the notches by the numbers corresponding to the one in use in the different figures.

It is our practice to construct the case J of two parts, so as to facilitate access to the interior of the same and replace or adjust the parts therein.

To prevent longitudinal movement of the sleeve F upon the spindle E, we provide an annular groove in said spindle E and attach to the sleeve F a tenon O, which projects into said groove, so that the sleeve F cannot slip longitudinally. This tenon O may be in the form of a plate extending through the slot in the side of said sleeve, wherein it may be secured by means of a screw O', access to the head of which may be gotten through alined openings passing through the gear-wheels C D, as indicated in dotted lines, Fig. 4. This is merely one convenient form of preventing longitudinal shifting of the sleeve F on said spindle E.

In operation the parts are shown in Fig. 4 to be locked—that is, it will be seen that the teeth G³ upon the rotatable sleeve G are in mesh with the teeth J' upon the stationary case J. Consequently the sleeve G cannot be rotated nor can the spindle E be rotated because of the square bearing E', which prevents the independent rotation of the spindle E and sleeve G. In this view it is also seen that the teeth G' project their full extent into the spaces between the teeth F'. Consequently the sleeves F and G are locked together and one cannot rotate independently of the other.

Inasmuch as the window A cannot be moved unless it is possible to rotate the gear-wheel D, and inasmuch as the window B cannot be moved unless it is possible to rotate the gear-wheel C, and inasmuch as said gear-wheels are shown in Fig. 4 to be locked, it follows that the windows A and B are locked in whatever positions they happen to be in. By moving the operating-handle M from the notch with which it is in engagement in Fig. 4 to the notch with which it is in engagement in Fig. 3 the teeth G³ on the sleeve G are freed from the stationary teeth J'. Thus the sleeve G may be rotated; but inasmuch as the teeth G' are not freed from the teeth F' the sleeve G cannot be rotated independently of the sleeve F. Consequently if when the parts are in this position the window A is moved up or down an opposite movement is necessarily imparted to the window B, because the moving of the window A rotates the gear-wheel D and the sleeve F, which necessarily rotates the sleeve G, which in turn necessarily rotates the spindle E through the square bearing E', which in turn rotates the gear C, and which in turn meshing with the rack B' imparts movement to the window B. Inasmuch as the racks A' B' are on opposite sides of the gear-wheels C D, it follows that the movement of the window A up or down imparts an opposite movement to the window B. It is possible by shifting the position of the operating-handle from that shown in Fig. 3 to that shown in Fig. 4 to lock the windows at any desired position. Now assume the operating-handle M is moved into the position shown in Fig. 2. This movement shifts the sleeve G still farther to the right and entirely frees the teeth G' from the teeth F'. In this position it is manifest that either window A or B may be moved up or down. The movement of the window A will rotate the sleeve F; but inasmuch as this sleeve is disconnected from the sleeve G and the spindle E no rotative movement will be imparted to these members, and consequently the window B will remain in whatever position it happens to be in. So, also, the raising or lowering of the window B will rotate the gear C, spindle E, and the sleeve G; but this movement will not be imparted to the sleeve F. Consequently the movement of the window B may be entirely independent of the window A. Thus the apparatus makes it possible to lock both the windows in whatever position they may happen to be, or it may so engage said windows and their associated parts that the opening of one will open the other or the closing of one will close the other, or they may be so freed from engagement that either window may be moved independently of the other. No greater freedom of action could be desired.

The case J may be inserted in a box in the window-frame in any way such as would suggest itself to the carpenter skilled in the art. The illustrations are purely conventional in this regard. It is preferred that the gear-

wheels C D be spaced slightly apart, so that in the event the teeth upon said gear-wheels are not in exact register sufficient space will be provided between said gear-wheels to admit of the rack A' entering said space and being shifted slightly, so as to register with the teeth on the gear-wheel C when it is desired to remove the window A. Manifestly either of the windows may be removed without removing the operating and locking mechanism.

What we claim is—

1. In a device of the character described, a pinion, a spring anchored at one end and secured at its other end to said pinion or an extension thereof, a second pinion concentric with the first-mentioned pinion and another spring, said second spring being anchored at one end and secured at its other end to said second pinion or an extension thereof, and means to engage and disengage said pinions.

2. In a device of the character described, a pinion, a spring anchored at one end and secured at its other end to said pinion or an extension thereof, a second pinion concentric with the first-mentioned pinion and another spring, said second spring being anchored at one end and secured at its other end to said second pinion or an extension thereof, means to engage and disengage said pinions, and means to lock said pinions against rotation.

3. In a device of the character described, a pinion, a spring anchored at one end and secured at its other end to said pinion or an extension thereof, a second pinion and another spring, said second spring being anchored at one end and secured at its other end to said second pinion or an extension thereof, and a clutch device carried by each of said pinions one of said clutch devices being movable laterally of said pinions to engage or disengage the other clutch device.

4. In a device of the character described, a pinion, a spring anchored at one end and secured at its other end to said pinion or an extension thereof, a second pinion and another spring, said second spring being anchored at one end and secured at its other end to said second pinion or an extension thereof, and a clutch device carried by each of said pinions one of said clutch devices being movable laterally of said pinions to engage or disengage the other clutch device, a locking-clutch carried by said movable clutch device and a stationary member adjacent said locking-clutch adapted to receive and hold the latter against rotation.

5. In a device of the character described, a pair of pinions, a shaft extending from one and a sleeve extending from the other and surrounding said shaft, a second sleeve mounted on the end of said shaft and free to shift lon-

gitudinally thereon but not to rotate independently thereof, clutch-teeth at the adjacent ends of said sleeves, and means to shift said second sleeve.

6. In a device of the character described, a pair of pinions, a shaft extending from one and a sleeve extending from the other and surrounding said shaft, a second sleeve mounted on the end of said shaft and free to shift longitudinally thereon but not to rotate independently thereof, clutch-teeth at the adjacent ends of said sleeves, means to shift said second sleeve, and means to lock said second sleeve and thereby both of said pinions when said teeth and locking means are in simultaneous operative engagement.

7. In a device of the character described, a pair of pinions, a shaft extending from one and a sleeve extending from the other and bearing upon said shaft, a second sleeve on that portion of said shaft extending beyond said first sleeve, said second sleeve being longitudinally but not rotatably mounted relatively to said shaft, long clutch-teeth at the adjacent ends of said sleeves and short clutch-teeth on another portion of said second sleeve, and a stationary member bearing short teeth to coact with said short teeth on said second clutch to lock all of said parts when both of said sleeves are interlocked.

8. In a device of the character described, a pair of pinions, means for interlocking the same, said means including a revolute member, a circular rotatable rack carried thereby and a pinion in mesh therewith, the axis of said rack being at an angle to the axis of said pinion.

9. In a device of the character described, a pair of pinions, means for interlocking the same and locking said interlocked pinions with a stationary part, springs connected with said pinions and with a suitable stationary part, and a rack in mesh with each of said pinions and windows carrying said racks.

10. In a device of the character described, a pair of toothed pinions, a rack for each of said pinions, a clearance-space between said pinions about equal to the thickness of one of said racks.

11. In a device of the character described, a pair of toothed pinions, a rack for each of said pinions, a clearance-space between said pinions about equal to the thickness of one of said racks, and interlocking means for said pinions.

Signed at New Britain, Connecticut, this 25th day of February, 1902.
